TABLE LAMP

Kurt Versen, Tenafly, N. J.

Application December 11, 1950, Serial No. 13,362

Term of patent 14 years

(Cl. D48—20)

To all whom it may concern:

Be it known that I, Kurt Versen, a citizen of the United States, residing at Tenafly, in the county of Bergen and State of New Jersey, have invented a new, original, and ornamental Design for a Table Lamp, of which the following is a specification, reference being had to the accompanying drawing, forming part thereof.

In the drawing:

Fig. 1 is a perspective view of a table lamp showing my new design; and

Fig. 2 is a perspective view thereof showing the reflector turned to another position.

I claim:

The ornamental design for a table lamp, substantially as shown.

KURT VERSEN.
